UNITED STATES PATENT OFFICE.

ALONZO B. ELY, OF GROTON, NEW YORK, ASSIGNOR TO CORONA TYPEWRITER COMPANY, INC., OF GROTON, NEW YORK, A CORPORATION OF NEW YORK.

TYPEWRITING-MACHINE.

1,398,321.

Specification of Letters Patent. Patented Nov. 29, 1921.

Application filed March 20, 1919. Serial No. 283,702.

To all whom it may concern:

Be it known that I, ALONZO B. ELY, a citizen of the United States of America, and a resident of Groton, county of Tompkins, 5 and State of New York, have invented certain new and useful Improvements in Type-writing Machines, of which the following is a specification.

This invention has relation to that type of 10 key-action which is usually employed for accent and underscore marks, where it is desired to print the character but to avoid feeding the carriage, as is well known; and a particular feature in this invention lies in 15 the provision of very simple means whereby the dead key or keys may be located at any position in the keyboard, the parts being so constructed and arranged that the dead-key lever, wherever located in the bank, may 20 be connected to the non-feed devices without the use of additional or special parts and without changing the usual arrangement of parts, as more fully hereinafter set forth.

My invention is shown in the drawings as 25 applied to a Corona key-action and escapement-operating mechanism, but it will be understood that the invention in its broader aspects may be applied to various types of mechanism, new as well as old. The Peter- 30 man Patent 1,121,040, dated December 15, 1915, shows one instance of the type of apparatus to which the invention may be applied.

In the drawings—

35 Figure 1 is a side elevation showing the invention applied to the well-known Corona key-action and escapement-operating device;

Fig. 2 is a perspective view of the essential parts of the invention;

40 Fig. 3 is a detail view of one of the detachable clips.

In the drawing annexed, the key-lever 5 is arranged to depress the universal-bar 6 when actuated, and the depression of this 45 bar serves, through the medium of a pair of side arms 7 and a link 8^a, to swing backwardly the pivoted bail 8 which, through the medium of a rearwardly-extending tappet 9, actuates the usual carriage-feed es- 50 capement 10. The swinging of the bail 8 backwardly also, in the usual construction, feeds the ribbon, but, as the feeding of the ribbon is not involved directly in the present invention, I have not illustrated the ribbon- 55 feeding devices.

To carry out my invention, I pivot the tappet 9 to the bail 8 by a horizontal pivot 11 to permit the tappet to be swung downwardly out of the path of the escapement, as shown in dotted lines in Fig. 1, so that when the tappet is thus adjusted to miss the escapement, the bail may be given its usual backward operative stroke without actuating the escapement. To pull the tappet 9 downwardly to non-feeding position, I employ a 60 link 12 pivotally connected to the tappet at its upper end and to an arm 13 at its lower end, said arm 13 being rigidly connected at its forward end to a rock-shaft 14 pivoted at its ends in the frame of the machine. 65 Affixed to the rock-shaft 14 is a depending arm 15, and pivotally connected to this arm is a horizontal link 16 whose forward end is pivotally connected to an upstanding ear 17 carried by the dead-key lever 5, so that when 70 this particular key-lever is operated the link 16 will rock shaft 14 and this action, through the medium of arm 13 and link 12, will pull down the tappet 9 and hold it down during 75 the working stroke of the escapement-actuating bail 8, thereby actuating the type-bars in the usual manner without operating the carriage-feed devices. The ribbon-feed, as heretofore stated, will be actuated in the usual manner through the movement of the 80 bail 8. I have not shown the type-bar action, but it will be understood that the type-bars are actuated in the usual manner from 85 the link 18 or in any other suitable way.

To enable the dead key to be placed in any 90 one of the key-positions in the keyboard, I make the depending arm 15 adjustable along the rock-shaft 14. This adjustability may be accomplished in any suitable way. As 95 a simple way of doing this, I affix the arm 15 to an open spring-clip 19 and adapt this clip to be engaged in notches in the upper and lower sides of the shaft, the notches being arranged in pairs. There will be a plurality of pairs of notches along the length 100 of the shaft, preferably as many pairs of notches as there are key-levers, so that the dead-key lever may be located in any key-position in the keyboard, and at the same time provide for a direct pull on the rock-shaft through the medium of the link 16.

The upper end of the link 12 may be connected pivotally to the tappet in any suitable manner, but I prefer providing the upper end of the link with a T-head 20 and 110

the tappet with a slot 21 extending fore-and-aft of the machine, so that the link 12 will not only have pivotal connection to the tappet, but will have a limited sliding connection therewith, to thus contribute to ease of action between the link and the tappet and also provide a simple and reliable means of connection between those two parts. I arrange a coil-spring 22 on the pivot-pin 11 to normally hold the tappet up against the T-head, a stop-lug 23 being arranged to arrest the tappet in its upward movement and hold it in a horizontal position in line with the lever or dog of the escapement 10.

15 When more than one of these keys is employed in the keyboard, it will be observed that when one of them is actuated the link 16 connected to the other dead-key or keys will have a pushing movement imparted to 20 it through the rocking of the shaft 14, so that, if this pushing movement on the links not in use were not compensated for, the resultant action would probably be that the links would bend or said other keys would 25 be actuated through the medium of the links 16. To avoid this, I provide a lost-motion connection somewhere between the rock-shaft and the key-lever adapted to come into play when any one of the links 16 is pushed 30 forwardly. A simple way of doing this is to connect each link to the upstanding lever-ear 17 by a horizontal slot 24. In this way, the operation of the dead-key lever will exert the desired pull upon the link 16, but 35 the other dead-key links 16, if additional ones be employed, will be permitted to slide forwardly freely to a sufficient extent to avoid injury to the parts or an undesirable action of the other dead keys.

40 As hereinbefore stated, the oscillation of the bail 8 will feed the ribbon by means well known; and it will be understood further that oscillation of this bail will also operate the ribbon-vibrator, an instance 45 of this being shown in Petermann Patent No. 1,121,044, dated December 15, 1914. As a matter of fact, this invention lends itself very nicely to use in connection with a shifting or movable member such as bail 8 which 50 is operated to not only feed the carriage but to shift the ribbon-vibrator to covering position, since in my apparatus I provide for giving such member a full throw even when operated by the dead-key action, thereby insuring a complete operation of the ribbon-vibrator. In the drawing, the ribbon-vibrator is shown at 25 and the mechanism for operating said vibrator at 26, this latter mechanism being connected to the bail 8.

55 The nature and scope of the invention having been thus indicated and its preferred embodiment having been specifically described, what is claimed as new is:

1. In a typewriting machine, the combination of character-key levers, an escapement-

operating element operable each time a key lever is actuated, a rock shaft extending transversely of the machine, means operable by said shaft for adjusting said element out of coöperative relation with the escapement, 70 said shaft having spaced pairs of oppositely disposed flat surfaces, a rock-arm having a U-shaped head adapted to embrace the bar and frictionally engage either of said pairs of flat surfaces, and a link detachably connected with one of said key levers at one end and connected at its other end with said rock arm.

2. In a typewriting machine, the combination of character key levers, a universal bar operable directly by the key levers, a vibrating member shiftable fore and aft of the machine by the universal bar, an escapement operating device pivotally held to said member to swing vertically relatively thereto, means for normally holding said device in a substantially horizontal operative position, a rock shaft, a rock-arm on said shaft, a link connecting said rock arm and the escapement operating device, and means connecting one of said key levers with said rock shaft for rocking the shaft to swing the escapement operating device downwardly to an inactive position when said key lever is actuated. 80

3. In a typewriting machine, the combination of character key levers, a universal bar operable directly by the key levers, a vibrating member shiftable fore and aft of the machine by the universal bar, an escapement operating device pivotally held to said member to swing vertically relatively thereto, means for normally holding said device in a substantially horizontal operative position, a rock shaft, a rock-arm on said shaft, a link connecting said rock arm and the escapement operating device, and individual operating connections between said shaft and certain of the key levers for rocking the shaft in a direction to swing the escapement operating device downwardly into an inactive position when either of said key levers is actuated. 100

4. In a typewriting machine, the combination of a fore and aft rocking frame extending transversely of the machine, a universal bar for rocking said frame, printing keys, key-levers carrying said keys adapted to engage and operate the universal bar, an escapement device, a tappet pivotally held to 115 said frame, means for normally holding the tappet in position to actuate the escapement device when the frame is rocked, and means connecting one of said key levers with the tappet for swinging the tappet about its pivot when the key-carrying end of the lever is depressed to render the tappet ineffective on the escapement device. 120

5. In a typewriting machine, the combination of an escapement device, a universal 130

- bar, character keys, key-levers carrying said keys and adapted to engage and operate the universal bar, a movable tappet support operable by the universal bar and shiftable fore and aft of the machine, a tappet for actuating the escapement device pivotally held to said support to swing vertically relatively thereto, means for normally holding the tappet in a rearwardly extending operative position, and means operable by one of said key levers for swinging the tappet downwardly about its pivot to an inoperative position when the key-carrying end of said lever is depressed.
6. In a typewriting machine, the combination of character key levers, a rocking frame, a universal bar for rocking the frame, an escapement operating tappet pivotally held to the frame to swing vertically relatively thereto, a rock shaft, a rock arm on said shaft, a link pivotally held at its lower end to said rock arm and having a sliding and pivotal connection at its upper end with said tappet, and means connecting one of said key levers with the shaft adapted to rock the shaft when said lever is actuated and thereby swing the tappet relatively to the rocking frame to an inoperative position.
7. In a typewriting machine, the combination of character key levers, an escapement operating element, a shiftable support for said element operable each time a key lever is actuated, a rock shaft extending transversely of the machine, individual operating connections between certain of said keys and the shaft for rocking the shaft, said connections having lost-motion therein, and means positively connecting said element and said shaft for shifting the element relatively to its support to an inoperative position by a partial rotation of the shaft through the medium of either of the key levers connected therewith.
8. In a typewriting machine, the combination of character key levers provided with short longitudinally extending slots, an escapement operating element, a shiftable support for said element operable each time a key lever is actuated, a rock shaft extending transversely of the machine, means operable by a rotary movement of said shaft for shifting the element relatively to its support to render the element ineffective, a rock arm, means for detachably connecting said arm with the shaft adjacent any desired one of said key levers, and a link pivotally connected at one end with said rock arm and provided with a hook at its other end adapted to engage in the slot in any desired one of said key levers.
9. In a typewriting machine, the combination of character key levers, a universal bar operable each time a key lever is actuated, an escapement operating element, a vibrat-
- ing frame supporting said element operable by the universal bar, a rock shaft, means operable by a rotary movement of said shaft for adjusting said element relatively to the frame to an ineffective position, a rock arm held to said shaft, and a link pivotally connected at one end with said rock arm and having a hook portion at its other end, one of said key levers having a slot therein through which the hook portion of the link extends.
10. In a typewriting machine, the combination of carriage feeding mechanism, character key levers, and means for silencing any desired key lever embodying a rock shaft extending transversely of the machine and provided with longitudinally spaced angular reduced portions, a rock arm provided with a spring clip adapted to grip either of the reduced angular portions of said shaft, a link pivotally held at one end to said arm and provided with means for detachably connecting the same with a desired key lever, and means operable by a rotary movement of the shaft for rendering the carriage-feeding means inactive.
11. In a typewriting machine, the combination of character key levers, a universal bar operable directly by said key levers, an inverted U-shaped frame pivotally supported to swing fore and aft of the machine and operable by the universal bar, an escapement device, a vertically swinging escapement-operating tappet pivotally held to said frame, a stop on the frame for determining the normal position of the tappet, a spring for normally holding said tappet against the stop in coöperative relation with the escapement device, a rockable member, a link connecting said rockable member with the tappet, and an operating connection between one of said key levers and the rockable member for swinging the tappet relatively to the frame by a movement of said member and link when said key lever is actuated.
12. In a typewriting machine, an escapement device, a universal bar, a rocking frame operable by the universal bar, character key levers, an escapement actuating tappet pivotally held to said frame, a spring normally holding said tappet in coöperative relation with the escapement device, a rock shaft extending transversely of the key levers across the machine, a rock arm rigidly held to said shaft, a tappet-deflecting link connected with the tappet and rock arm, and an interchangeable operating connection provided at opposite ends thereof with means for separably attaching the same to said shaft and either of the key levers.

This specification signed this 3d day of 125
March, A. D. 1919.
